CLAIM

The ornamental design for a combined suntan lotion distributor and cap therefor, as shown and described.

DESCRIPTION

FIG. 1 is an exploded perspective view of the suntan lotion distributor shown with the telescopic handle in the extended position;

FIG. 2 is a bottom view of the design shown with the cover removed for ease of illustration;

FIG. 3 is an exploded rear view of the design;

FIG. 4 is a top view of the design with the cover removed;

FIG. 5 is a bottom view of the distributor portion of the design shown with the handle in the folded position;

FIG. 6 is an exploded front view shown with the handle in the folded position;

FIG. 7 is an exploded left side view shown with the handle in the extended position; and,

FIG. 8 is a perspective view of the assembled design showing the handle in the folded position.
